UNITED STATES PATENT OFFICE.

HARRISON D. STERRICK, OF PITTSBURG, PENNSYLVANIA.

DESIGN FOR A COMBINED PICTURE GLASS AND FRAME.

No. 39,665.

Specification for Design.

Patented Nov. 10, 1908.

Application filed June 23, 1908. Serial No. 440,050. Term of patent 7 years.

To all whom it may concern:

Be it known that I, HARRISON D. STERRICK, a citizen of the United States, residing at Pittsburg, in the State of Pennsylvania, have invented a certain new and useful and original ornamental Design for a combined Picture Glass and Frame, of which the following is a specification, reference being made to the accompanying drawing, forming a part thereof.

The figure shows a front view of the picture glass and frame, showing my design.

I claim

The ornamental design for a combined picture glass and frame as shown.

HARRISON D. STERRICK.
